D.N.B. Coffin, Jr.

Shoe Fastening.

N° 38,373,

Patented May 5, 1863.

UNITED STATES PATENT OFFICE.

DAVID N. B. COFFIN, JR., OF WOBURN, MASSACHUSETTS.

IMPROVEMENT IN BOOTS AND SHOES.

Specification forming part of Letters Patent No. 38,373, dated May 5, 1863.

To all whom it may concern:

Be it known that I, DAVID N. B. COFFIN, Jr., of Woburn, in the county of Middlesex and State of Massachusetts, have invented a new and useful Improvement in Boots and Shoes; and I do hereby declare that the following is a full and exact description thereof, reference being had to the accompanying drawings, and to the letters of reference marked thereon, making part of this specification.

The nature of my invention relates to the means employed for fastening and unfastening the boot or shoe; and it consists of the arrangement of a series of buttons and a series of holes, eyelets, loops, or studs on the different parts, which are to be drawn toward and secured at each other, these buttons on the one part and holes, eyelets, loops, or studs on the other being arranged to receive a lacing, string, or cord, alternating from one member of one series to one of the other, and vice versa, as may be seen in the drawings, so that the unlooping of the string from one button loosens the loop upon the next, and by unlooping one or more of the loops from their respective buttons the fastening of the shoe or boot is loosened while the ends of the string remain fast, and so that the looping on again of such loops of the string fastens again the boot or shoe, substantially as hereinafter more fully illustrated and described.

With reference to the accompanying drawings, Figure 1 is a perspective drawing of the improved boot, representing it as it appears laced up upon the foot, the eyelets being hidden by a finish made to lap over and cover them. Fig. 2 is a drawing of a heavy boot for men's wear, showing a series of loops, instead of eyelets, (these loops must not be mistaken for loops of the lacing,) on the part opposite to that on which the buttons are set, the loops being formed by the leather being folded and stitched, and having scallops cut out. Fig. 3 shows the part opposite that on which the buttons are set, made double and connected with a series of studs around which the lacing is passed between the two thicknesses of leather, the leather being stitched or otherwise connected between the studs to prevent the loops of the string getting in between out of the reach of the fingers. Fig. 4 is a drawing of a boot for ladies' wear, the toe, heel, and sole

being of leather and other parts of cloth, the part opposite to that having the buttons being furnished with eyelets to receive the lacing alternately with the buttons. Fig. 5 is a drawing of the front of a shoe, in which the two parts of the shoe, made to lap the one upon the other, are each furnished with a strip stitched on purposely to receive the eyelets and buttons, and furnishing another style of finish suited to my improvement. Figs. 6 and 7 are different views of a heavy boot for men's wear with eyelets to receive the lacing alternately with the buttons. Fig. 8 is a drawing of the front part of a simple style of shoe, in which the parts bearing the buttons and eyelets do not lap over each other, but are furnished with a tongue underneath. Fig. 9 is a drawing of a child's heavy shoe similar in style to Fig. 2, but varying in finish. Fig. 10 is a drawing of the improved boot unfastened and ready to be put on or off from the foot. Fig. 11 shows two views of a button made concave around the eye and suited to keep the lacing from slipping off the button after being loosened. Fig. 12 shows a button made with a base or shank extending to a little distance from the neck to prevent the action of the string from tipping the button, and Fig. 13 is a little different form of the same. Fig. 14 is a drawing of a button furnished with a sheave or friction-roller upon its neck to make the string or lacing render more freely, and Fig. 15 shows a button riveted in so as to be free to turn in the leather so to facilitate the rendering of the lacing. These peculiarly-constructed buttons are useful but not essential to my improvement, as a common button answers a good purpose.

When it is desired to modify the style of boot to show a row of buttons on both sides, one row of buttons may have an additional eye underneath to pass the lacing through, as through an eyelet, or the single eye may be made large enough to secure the buttons by and receive the lacing to, so producing uniformity of finish on both sides or parts of the boot.

My improvement I have denominated the "button-laced boot and shoe," and that others skilled in the art may be enabled to make and use it, I will proceed to describe its construction and operation.

The boot is made of any of the materials

commonly employed in the art. The boot or shoe is for the most part made in the same manner and various styles, forms, sizes, &c., as other boots, except those parts which are made to receive the fastening device. These must be adapted to and furnished with a series of buttons, *a*, on one part and a series of holes, eyelets, loops, or studs, as *c d e f*, on the other part, so as to admit of the application of a string or lacing, *g*, substantially in the manner shown in the drawings.

The operation is substantially as follows: I attach the end of the lacing, by tying or otherwise, to a button, as at *h*, then pass it through an eyelet, as at *i*, thence around the next button, thence through the next eyelet, thence around the next button, and through the next eyelet, and so on to the end of the series. I then put on the boot or shoe (or it may be put on first) and adjust to the foot, drawing the lacing to the proper tension. I then fasten the lacing, as at *J*, by tying or otherwise. Now, when I wish to take off the boot or shoe I have no untying of the lacing to do but simply to throw off one or more of the loops *k l*, &c., of the lacing from the buttons, when the fastening of the boot is at once relieved and the parts are loosened, as see Fig. 10, and the foot released. It will be observed that the loosening of the lacing from the buttons is very easily and expeditiously performed with the fingers without button-hooks or other appliances, the loops are so perfectly accessible and easily thrown off, and then, when one loop of the lacing is released it relieves the tension on the adjacent ones, making this almost the simplest possible fastening to release or unfasten. Now, in readjusting and fastening the boot there is no sewing or weaving in of the lacing to do, but simply to readjust one after another of the few loops of the lacing, which have been unbuttoned, about their respective buttons, and the boot or shoe is fast again upon the foot.

Some of the advantages of my improvement

I will mention—viz: The boot is much more easily fastened and unfastened than the common laced boot, and is quite as neat and genteel in appearance. It does not, like the elastic-gore or congress boot, hug the ankle too closely when new or become slouched or too loose when old, as the means of adjustment are inherent. It does not, like the common button-boot, require a button-hook to operate it, nor grow ragged as they do about the button-holes. Thus, my improvement combines most of the advantages of the common-laced boot, the congress and the button boot, and is free from many of their disadvantages.

Having pointed out the distinguishing features of my improvement, and set forth the construction and operation thereof, I claim—

The button-laced boot and shoe as a new article of manufacture, the distinguishing feature of which consists of the arrangement of a series of buttons and a series of holes, eyelets, loops, or studs upon the different parts which are to be drawn together and secured to each other, these buttons on the one part and holes, eyelets, loops, or studs on the other being arranged to receive a lacing, string, or cord, alternating from one member of one series to one of the other, and vice versa, so that the unlooping of the string from one button loosens the loop upon the next, and unlooping one or more of the loops from their respective buttons the fastening of the boot or shoe is loosened while the ends of the string remain fast, and such loops of the string may be looped on again, so refastening the boot or shoe, substantially as herein set forth.

In testimony whereof I have hereunto set my hand and seal.

DAVID N. B. COFFIN, JR. [L. S.]
